UNITED STATES PATENT OFFICE.

JULIUS GIEBEL AND FRED H. ZIMMERMAN, OF FREMONT, OHIO.

SINKER OR HUB FOR USE IN MANUFACTURING DIES.

1,247,524.

Specification of Letters Patent. Patented Nov. 20, 1917.

Application filed January 4, 1917. Serial No. 140,594.

To all whom it may concern:

Be it known that we, JULIUS GIEBEL and FRED H. ZIMMERMAN, both citizens of the United States of America, residing at Fremont, in the county of Sandusky and State of Ohio, have invented certain new and useful Improvements in Sinkers or Hubs for Use in Manufacturing Dies, of which the following is a specification.

This invention relates to sinkers or hubs for sinking dies and its object is to provide an improved article of this nature constructed in such manner as to save time, labor and material in the completion of the die constructed thereby and also constructed in such manner that the employment of skilled labor may be in some measure dispensed with because the improved die or sinker minimizes the danger of mistakes and errors, makes every impression uniform, simplifies the finishing of the die and insures sharp corners or edges on the finished die irrespective of the hand labor performed upon the die.

Further objects and advantages of the invention will be set forth in the detailed description which now follows:

In the accompanying drawing,

Figure 1 is a plan view of a hub or sinker constructed in accordance with the invention.

Fig. 2 is a side elevation thereof,

Fig. 3 is a transverse, vertical section therethrough and Fig. 4 is a sectional view of a die formed by the tool before the surface of the same is dressed off.

Like numerals designate corresponding parts in all of the figures of the drawing.

The hub or sinker is a tool made in the shape of the article that is to be stamped out by the finished die. In making the die the block of which the die is to be made is heated to the proper temperature and the sinker or hub is pounded or driven into it leaving an impression the shape of the sinker or hub.

Heretofore it has been customary to pound the sinker or hub into the block of steel to a depth determined more or less by guess work and then dress off the top of the die block to secure an impression of the proper depth. With the hubs or sinkers heretofore employed it has been difficult to secure sharp

edges at the upper face of the die. By the employment of the hub or sinker constituting the present invention sharp edges are secured at the upper face of the die and such indications are formed upon the upper face of the die block as will indicate to the workman the exact point to which the top of the die block is to be finished.

Referring to the accompanying drawing 5 designates a base block having formed upon its upper face any suitable shape such as is indicated at 6 and which shape when 65 pounded into a heated block of steel A, from which the die is to be formed is adapted to produce an impression or cavity a therein, which corresponds to the configuration of the shape 6.

The present invention resides particularly in forming a ledge 7 around the shape 6 which ledge substantially conforms to the configuration of the shape 6 and this ledge is separated from the shape by a continuous 75 gutter 8.

In operation the presence of the gutter prevents the heated steel in the die from flowing or escaping from direct contact with the sinker or hub and insures sharp corners 80 or edges on the finished die as well as strengthening the sinker or hub.

The ledge in addition to serving as an element in the formation of the gutter acts as a marker to leave an impression upon the 85 die block at b which serves as a guide to the mechanic and indicates the point to which the top of the die block is to be dressed. Consequently the employment of highly skilled labor is rendered unnecessary, the 90 danger of mistakes and errors is minimized and the finishing of the die is simplified.

Having described our invention what we claim is:—

1. A hub or sinker comprising a base 95 block, a shape formed thereon, a ledge surrounding said shape and a gutter formed between said ledge and said shape.

2. A hub or sinker comprising a base 100 block, a shape formed thereon, a ledge which projects above the face of the base block but lies below the face of the shape and a gutter formed between said ledge and said shape.

3. The herein described method of producing dies which consists in heating a block 105

of metal, forcing into said block a tool corresponding in shape to the article to be produced by the die and by the same act providing means surrounding the shape to prevent a flow of the metal of the die away from the shape at the termination of the compressing operation.

In testimony whereof we affix our signatures in presence of two witnesses.

JULIUS GIEBEL.
FRED H. ZIMMERMAN.

Witnesses:

CHESTER A. CULBERT,
JOHN KUPPINGER.
